UNITED STATES PATENT OFFICE.

WILLIAM B. EASTON, OF CHICAGO, ILLINOIS, ASSIGNOR TO THE FRASER & CHALMERS, OF SAME PLACE.

AMALGAMATING-PAN AND SETTLER.

SPECIFICATION forming part of Letters Patent No. 593,767, dated November 16, 1897.

Application filed May 25, 1897. Serial No. 638,154. (No model.)

To all whom it may concern:

Be it known that I, WILLIAM B. EASTON, a citizen of the United States, residing at Chicago, in the county of Cook, State of Illinois, have invented certain new and useful Improvements in Amalgamating-Pans and Settlers, of which the following, with the accompanying drawings, is a full, clear, and exact specification.

10 My invention relates to amalgamating-pans and settler-pans used in the extraction of precious metals from the ore.

In the process of amalgamation it is very objectionable to have the slightest amount 15 of grease or oil come in connection with the slimes.

The object of the invention is to prevent the oil used in lubricating the spindles from getting into the pan and mixing with the 20 slimes.

The invention consists in the construction and combination of parts described herein and defined in the claim.

Referring to the accompanying drawings, 25 Figure 1 is an elevation, partly in vertical section, of a settler-pan and enough of its operating mechanism to illustrate the invention. Fig. 2 is a horizontal section of a settler-pan on line $\alpha\alpha$ in Fig. 1.

30 Like characters of reference refer to like parts throughout the drawings and specification.

1 is the settler-pan, and 1^a is the bottom thereof. Bolted or otherwise rigidly secured 35 to the bottom 1^a is the pan-cone 2, which passes up through the center of the pan. The cone 2 is hollow, and through it passes the spindle 3, having the miter-gear 4 on its lower end in mesh with the bevel-gear 5 on the 40 driven shaft. Surrounding the pan-cone 2 is the driver 6, which may be raised or lowered by means of the hand-wheel 7, attached to the driver-nut 6^a, which is threaded onto the spindle-stem 3^a. The upper portion of the 45 driver 6 is cylindrical in form, while the lower part is in the form of a spider, the four legs 6^a of which are attached to the upper side of the muller-plate 8. The shoes 9 are attached to the under side of said muller-plate.

In the upper portion of the driver 6 is the 50 annular channel 6^b, which receives the upper part of a piece of pipe 13, called an "oil-guard." The lower edge of the oil-guard fits inside of the annular dish-shaped upper extremity 2^a of the pan-cone 2. 55

The interposition of the oil-guard in the annular chamber 6^c between the spindle 3 and the driver 6 prevents the lubricant from being thrown by centrifugal force from the spindle to the inner wall of the driver, and 60 from there passing down said inner wall into the pan. By placing the oil-guard as above described the centrifugal force throws the oil from the spindle to the inside of the oil-guard, from whence it runs down into the 65 dish-shaped upper end of the pan-cone and follows down the spindle. The annular channel 6^b is deep enough to admit raising the driver any desired distance without freeing the upper end of the oil-guard. 70

The annular chamber 10 constitutes an oil-cup into which oil finds its way through the opening 11 from the channel 12, formed in the upper side of the oil-cup. From the oil-chamber 10 the oil passes down around the 75 spindle 3. In the sides of the spindle 3 are oil-grooves 3^b, which carry oil to the whole circumference of the bearing in which the spindle turns and also carry oil into the annular chamber 6^c inside of the oil-guard. 80

What I claim as my invention, and desire to secure by Letters Patent, is—

In amalgamating-pans or settlers, the combination of a spindle, a pan-cone provided with a dish-shaped top, a driver-head fixed 85 at the upper end of the spindle and having an annular channel, and an oil-guard, the upper end of the oil-guard being loosely inclosed in the annular channel in the driver-head, and having its lower end resting in the 90 dish-shaped top of the pan-cone, substantially as described.

In testimony whereof I affix my signature in the presence of two witnesses.

WILLIAM B. EASTON.
